UNITED STATES PATENT OFFICE.

SHUBAEL COTTLE, OF NEW YORK, N. Y.

COLLAR-BUTTON.

SPECIFICATION forming part of Letters Patent No. 311,107, dated January 20, 1885.

Application filed November 22, 1884. (No model.)

To all whom it may concern:

Be it known that I, SHUBAEL COTTLE, a citizen of the United States, residing at New York, in the county of New York and State 5 of New York, have invented certain new and useful Improvements in Collar-Buttons, of which the following is a description.

I have obtained Letters Patent of the United States for a collar-button whose back is formed 10 in one piece with the hollow post, and which, by reason of its superiority, has come into quite extensive use.

My present invention is an improvement thereon; and it consists in constructing the 15 back double, as hereinafter described.

I propose constructing the said back either with or without a small central aperture communicating with the post, and in accompanying drawings both modes of construction are 20 represented, Figures 1 to 4, inclusive, exhibiting one mode, and Figs. 5 to 8, inclusive, the other.

I will preface further description of these modes of manufacture by stating that, inasmuch as they involve *per se* nothing essentially novel, save in respect to the result or article produced, I omit detailed description of the special successive manipulations required to draw or swage the blank into the 25 ultimate forms desired, since they (the manipulations) are well known, as will be readily understood or devised by those skilled in the art.

Referring, then, in the first instance, to 30 Figs. 1 to 4, inclusive, I will state that the first step in the process of manufacture of a button having a double back with a central aperture therein consists in drawing or swaging a blank—to wit, a thin metal disk—into the form 35 represented by Fig. 1, wherein the hollow post *a* is shown projecting from the flat upper (or inner) portion of the back *b*, whose outer (lower) portion yet remains to be formed from the pendent circular flange *c*. In the next swaging operation this right-angular flange *c* is

upset and deflected inward at an acute angle, as shown in Fig. 2, and by the next two operations it is reduced to parallelism with the inner (upper) portion, as illustrated in Figs. 3 and 4. Thus a collar-button is produced 50 whose back is double, and the face or outer side of which has a minute opening coincident and communicating with the hollow post.

Referring now to Figs. 5 to 8, inclusive, I represent in Fig. 5 the form which the blank 55 (disk) is made to assume by the first drawing operation—that is to say, the form of a hollow cylinder, *a'*, having one end closed. By the succeeding steps or operations the body of such cylinder is gradually contracted and 60 elongated, and the bottom slightly expanded (see Figs. 6, 7) until the form shown in Fig. 8 is attained—that is to say, a double back, *b'*, whose face or outer (lower) portion is entire or without an opening. Thus, by either 65 mode of manufacture above described I produce a collar-button whose back is double and yet solid, or in one piece with the hollow post, and which is, therefore, superior in the important qualities of solidity, strength, durability, and ornamental finish or effect.

It is obvious that sleeve-buttons of a certain class may be manufactured in the same manner and form as collar-buttons.

What I claim is—

1. The improved collar - button, substantially as described, the same consisting of the double back and hollow post formed in one piece, and said post being provided with a suitable head.

2. The collar - button having a double or hollow back, *b'*, which is formed entire or without an opening therein, and in one piece with the hollow post, *a'*, which is provided with a suitable head, substantially as shown 85 and described.

SHUBAEL COTTLE.
